(57) **CLAIM**

The ornamental design for a cell phone stand holder, as shown and described.

DESCRIPTION

FIG. 1 is a perspective view of a cell phone stand holder, showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a use state view; and,

FIG. 9 is an enlarged view of Portion of FIG. 8.

The broken line showing of cell phone stand holder is for the purpose of illustrating environment and forms no part of the claimed design.
